UNITED STATES PATENT OFFICE.

JAMES B. JARMIN, OF DAVENPORT, IOWA, ASSIGNOR TO AMERICAN PLOW COMPANY, OF MADISON, WISCONSIN, A CORPORATION OF WISCONSIN.

PLOW.

SPECIFICATION forming part of Letters Patent No. 766,258, dated August 2, 1904.

Application filed August 22, 1902. Serial No. 120,677. (No model.)

To all whom it may concern:

Be it known that I, JAMES B. JARMIN, a citizen of the United States of America, and a resident of Davenport, Scott county, Iowa, have 5 invented a certain new and useful Improvement in Plows, of which the following is a specification.

My invention relates to wheeled or sulky plows of that type in which all framework is 10 dispensed with and in which the front and rear furrow-wheels and also the land-side wheel are connected directly with the plow-beam. It is usually the practice in a plow of this character to provide shifting connections 15 between the plow-beam and the wheels and also to provide one or more levers for controlling the adjustments of these wheels relatively to the plow and beam, so as to permit the driver to raise and lower the plow.

Generally stated, it is the object of my invention to provide a simple, comparatively inexpensive, and highly-efficient wheeled plow 20 of the foregoing character.

A special object is to provide an improved 25 form of shifting connection between the plow-beam and the rear furrow or caster wheel.

Another object is to provide an improved system of leverage for simultaneously controlling all of the wheels.

A further object is to provide an improved 30 lever arrangement whereby the driver may employ a foot-lever in conjunction with one or more hand-levers for controlling the wheels.

Another object is to provide a plurality of 35 improved shifting connections between the wheels and plow-beam and to arrange the shifting connections in such manner that the plow may be raised and lowered without lengthening or shortening the wheel-base.

It is also an object to provide certain 40 details and features of improvement tending to increase the general efficiency and serviceability of a wheeled plow of this character.

To the foregoing and other useful ends my 45 invention consists of matters hereinafter set forth and claimed.

In the accompanying drawings, Figure 1 is a furrow-side elevation of a wheeled plow

embodying the principles of my invention, the plow and beam being shown raised from 50 the ground. Fig. 2 is a similar elevation, but showing the plow lowered into the ground. Fig. 3 is a land-side elevation of my improved wheeled plow, the plow and beam and other parts being in the same position as illustrated 55 in Fig. 2. Fig. 4 is a plan of my improved plow with the different parts in the relative positions shown in Fig. 2. Fig. 5 is an enlarged vertical section on line 5 5 in Fig. 2. Fig. 6 is a detail section on line 6 6 in Fig. 4. 60 Fig. 7 is an enlarged horizontal section on line 7 7 in Fig. 3. Fig. 8 is an enlarged vertical detail section of the shifting connections between the plow-beam and rear furrow or 65 caster wheel. Fig. 9 is a horizontal detail section on line 9 9 in Fig. 8. Fig. 10 is a detail cross-section on line 10 10 in Fig. 3. Figs. 11 and 12 are detail views illustrating the construction of the jointed or reticulated connection between the foot-lever and the 70 crank-axle.

As thus illustrated my improved wheeled plow comprises, preferably, a plow A and beam B. These can, it will be understood, be of any suitable known or preferred form. 75

The wheels for supporting the plow and beam preferably comprise front and rear furrow-wheels C and D and also a land-side wheel E. The said front furrow-wheel is, it will be observed, preferably mounted upon the 80 lower outturned end portion of the stem c. In a similar manner the rear furrow or caster wheel D is preferably mounted upon the lower end of the caster-wheel stem d. The land-side wheel, however, can, if such is desirable, be 85 mounted upon the transversely and horizontally disposed crank-axle E'.

The shifting connection between the front furrow-wheel and the plow-beam can consist of a bracket c', provided with a sleeve portion 90 c'', adapted to slide up and down upon the stem c. With respect to the adjustment of this

wheel relatively to the plow-beam the said bracket can be adapted to provide a bearing for the short shaft c'', having a toothed wheel 95 c''' mounted upon its inner end. The outer end

of this shaft can be provided with a crank-arm c^5 , the latter being connected by a link or pitman c^6 with the casting c^7 , mounted upon the upper end of the stem c . The tongue F 5 is preferably pivotally secured to this casting c^7 , so as to permit the team to control the front furrow-wheel.

My improved shifting connection between the plow-beam and the rear furrow or caster wheel D preferably consists of a bracket G , having its forward end secured to the curved portion of the plow-beam and having its rear end portions g adapted to slide up and down upon the pipe g' , which latter, it will be observed, 10 is mounted upon the cylindric stem of the said caster-wheel. With the provision of the bolts g^2 and the slots g^3 it will be seen that these portions g of the bracket can be adjusted laterally relatively to the balance of 15 the machine, so as to permit the rear furrow or caster wheel to be adjusted laterally relatively to the plow in accordance with the character of the soil. The driver's seat H can be mounted upon the sleeve or collar h , which latter is preferably secured to the pipe g' . The lower end of the said pipe normally rests upon the collar g^4 , which is secured upon the stem of the caster-wheel. An arm g^5 can be clamped upon the lower end of the pipe, in 20 which the caster-wheel stem is free to turn, and the forward end of this arm can be connected with the cranks g^6 by means of the vertically-disposed pitman g^7 . A toothed wheel g^8 is preferably mounted upon the outer 25 end of the crank-shaft carrying the cranks g^6 . With respect to the lateral adjustment of the rear furrow or caster wheel the arm g^5 can be made in two parts, as shown in Fig. 9, and with the provision of the bolts g^9 and the slots g^{10} the two parts of this arm can be adjusted 30 laterally relatively to each other when it becomes desirable to shift the caster-wheel to one side or the other, according to the character of the soil in which the plow is to operate. 35

As shown more clearly in Fig. 4, the upper end of the rear furrow or caster wheel stem is preferably provided with a laterally-extending crank-arm g^{11} , while the upper end 40 of the front furrow-wheel stem is provided with a similar arm c^8 . These two laterally-extending arms are preferably connected by a rod I . With this arrangement the tongue, it will be seen, is connected to control both 45 the front and rear furrow-wheels. At the same time it will be seen that the two vertically-disposed stems which are thus turned or rotated by the tongue afford standards or uprights upon which the plow structure is 50 free to slide up and down when it is desirable to raise or lower the plow.

With respect to the simultaneous adjustment of the front and rear furrow-wheels relatively to the plow and beam the sprocket-wheels c^9 and g^8 are preferably connected by 55

a chain belt J . With this arrangement a simultaneous rotation of the two toothed or sprocket wheels can be had for the purpose of simultaneously operating the two shifting connections between the front and rear furrow-wheels. 70

The land-side wheel E is, as stated, preferably mounted on a crank-axle, which latter is supported for rotation in the bracket-bearing e . This bearing, it will be observed, is secured to the plow-beam and extends outward to the land side of the plow. With respect to a desirable independent adjustment or control of the land-side wheel the said crank-axle is preferably provided with a loosely-mounted crank-arm e' and also with a rigidly-secured rack e^2 . The lever e^3 is preferably rigid with the swinging arm e' and is thus adapted for controlling or adjusting the land-side wheel independently of the balance of the machine. The usual locking-bolt on the said lever is, it will be understood, arranged to engage the said rack, and in this way the said wheel can be adjusted and locked in any position relatively to the transverse or straight portion of the axle. 80

Now with a view to providing means whereby a foot-lever can be employed for simultaneously controlling all three wheels, so as to permit the driver to raise and lower the plow 95 without using either hand, I provide the crank-axle with a rigidly-secured arm K and connect this arm with the foot-lever L by means of a link k . The joint or reticulation between this link and the arm l of the foot-lever is, it will be observed, of a character as to readily break joint upward, but of such character as to be positively locked or held against movement in a downward direction. This will be readily understood by referring 100 to Figs. 11 and 12, wherein it will be seen that the arm of the foot-lever can be provided with a lip or projection l' , adapted to extend over the link. This jointed portion of the system of leverage thus provided can also be provided with a foot-piece l'' to enable the driver to return the parts to the position shown in Fig. 3—that is to say, to permit the driver to press the jointed connection forward and downward from the position shown in Fig. 1, so as to force 115 the plow into the ground and lock it against rising. When the link K and the foot-lever L are in the positions shown in Fig. 3, it will be seen that the joint thus provided between the two serves to lock the plow against rising. 120 With this arrangement the driver can raise the plow from the furrow by simply placing his foot upon the lever L , so as not only to rotate the crank-axle, but so as also to operate the shifting connections between the front and rear furrow-wheels. This adjustment of the front and rear furrow-wheels through the medium of the foot-lever and the crank-axle is preferably accomplished by providing the outer end of the axle with an arm M , which is 125 130

connected by the plate *m* with the link belt *J*, extending around the two sprocket-wheels. With this arrangement it will be seen that the driver in rotating the crank-axle by means of 5 the foot-lever must necessarily cause a shifting movement on the part of the link belt and a consequent rotation of the two sprocket-wheels, the latter resulting, of course, in an up-and-down sliding movement of the plow-beam upon the stems of the front and rear furrow-wheels. Thus it will be seen that the foot-lever can be employed for simultaneously controlling all three wheels, so as to 10 raise and lower the plow, and that the auxiliary hand-lever *c*³ can be employed for independently controlling the land-side wheel, so as to permit the driver to readily level up the plow. In thus raising and lowering the plow 15 it will be seen that the driver does not lift his own weight, inasmuch as the seat is supported solely by the rear furrow or caster wheel through the medium of the sleeve or pipe *g'*. In this connection it will be seen that the said pipe or sleeve is held positively 20 against any rotation in the casting *G* by reason of the pitman *g'* being held firmly against lateral movement by the two cheeks or parts *g*¹². Thus the plow-beam is free to slide up and down upon the stem of the rear furrow or 25 caster wheel, and at the same time the said wheel supports the weight of the driver without causing the driver's seat to swing from side to side with the motion of the wheel. In other words, when the course of the machine is 30 altered the seat remains in its proper position and does not turn when the two wheels are turned by a lateral deflection of the tongue.

In order that the driver may, if such is necessary or desirable, employ either hand to assist the foot-lever in raising or lowering the plow, I provide the crank-axle with a loosely-mounted hand-lever *N*. This hand-lever is provided with a couple of locking devices, as 40 shown in Fig. 2, one adapted to engage the upper end of the arm *M*, which latter, as stated, is rigid with the crank-axle, and the other engages the rock *h* on the plow-beam. With this arrangement this auxiliary lever can be locked to the crank-axle through the 45 medium of the arm *M*, and in such case it can be grasped by the driver and employed for rotating the crank-axle, and thereby causing the described simultaneous adjustment or control of all three wheels. As another advantage 50 this hand-lever can be simply employed as a stop or gaging device for regulating the depth to which the plow is adjusted. For example, this lever can be thrown forward to the desired point and can then be allowed to 55 remain in such position while the plow is raised and lowered by means of the foot-lever. In such case the plow can only be lowered until the arm *M* strikes the locking device on the lever, and in this way, as stated, 60 this lever *N* acts as a stop to limit the down- 65

ward movement of the plow. Thus the hand-lever *N* can be employed as a gage or stop for regulating or determining the depth of the furrow.

The two vertical standards provided by the 70 stems of the front and rear furrow-wheels permit the plow-beam and the rigid structure connected with it to slide up and down vertically without in any way lengthening or shortening the wheel-base. In other words, the 75 two stems always remain parallel regardless of the position of the plow, and the distance between these two stems also remains constant, thereby insuring a wheel-base which remains the same at all times. In this way 80 the plow is readily and easily raised and lowered without varying and changing the distance between the front and rear furrow-wheels, and thereby, as stated, without altering 85 the character of the wheel-base.

With respect to the raising and lowering of the plow it will be observed that the crank-arm *c*⁵ can be somewhat longer than crank *g*⁶, so as to give the point of the plow considerably more up-and-down movement than the 90 heel. In this way the plow when raised from the ground will have its toe or point held in a more or less elevated position relative to its heel, and when in the ground the plow will have the requisite or desired dip—that is to 95 say, the plow-point will always be below the heel when the plow is in the ground, thereby insuring against drag or unnecessary friction.

With further respect to the shifting connections between the rear furrow or caster wheel and the plow-beam it will be seen that the construction is such as to insure a high degree of rigidity and strength, thereby insuring against loose joints and the play or lost motion which might otherwise result from 100 long or continued use of the plow.

With the provision of the foot-lever the driver can easily raise and lower the plow without letting go of the lines, and at the same time and with the provision of the second auxiliary lever the driver can, if necessary, use one hand for simultaneously controlling all three wheels. Thus my improved plow has substantially all of the adjustments which are known to be necessary or desirable to the 105 proper working of a plow of this character, and at the same time the construction is light and simple and in addition of a character to insure a high degree of strength and rigidity. Obviously, however, there are many 110 advantages in my construction which will be instantly recognized by those skilled in the art and which for this reason I need not mention.

What I claim as my invention is—

1. A wheeled plow comprising a suitable plow and beam, front and rear furrow-wheels, a land-side wheel, a vertically-disposed stem upon which the rear furrow-wheel is mounted, a vertically-disposed stem upon which the 115 120 125 130

- front furrow-wheel is mounted, a crank-axle upon which the land-side wheel is mounted, a foot-lever having a jointed connection with said crank-axle, suitable connections where-
5 by a rotation of said axle causes the plow and plow-beam to slide up and down upon said stems, and an auxiliary lever for independently controlling said land-side wheel.
2. A wheeled plow comprising a suitable plow and beam, a plurality of wheels including a rear furrow-wheel, a vertically-disposed stem on which said furrow-wheel is mounted, a bracket connecting said stem with said plow-beam, said bracket being adapted to slide up
10 and down upon said stem, a driver's seat carried by said stem, the said plow being thereby free to rise and fall without altering the position of the driver's seat, and a manually-adjustable member for simultaneously controlling all of said wheels.
3. A wheeled plow comprising a suitable plow and beam, a plurality of supporting-wheels including a rear furrow-wheel, a vertically-disposed stem upon which said furrow-
15 wheel is mounted, a bracket connecting said stem with said plow-beam, said bracket being adapted to move up and down upon said stem, a driver's seat supported by the stem, the plow and beam and bracket thereby being free to
20 rise and fall without lifting and lowering the driver, a lever connected and arranged for simultaneously controlling all of the said wheels, and an auxiliary lever connected and arranged for independently controlling one of said
25 wheels.
4. A wheeled plow comprising a suitable plow and plow-beam, a plurality of supporting-wheels including front and rear furrow-wheels, vertically-disposed stems on which
30 said furrow-wheels are mounted, brackets connecting said stems with said plow-beam, the stems being mounted to turn or rotate relatively to the brackets, and manually-controlled means including a lever for causing the plow
35 and beam and brackets to slide up and down upon said stems.
5. A wheeled plow comprising a suitable plow and beam, a plurality of supporting-wheels including a rear furrow-wheel, a vertically-disposed stem upon which said furrow-
40 wheel is mounted, a sleeve on said stem, a bracket connecting said plow and beam with said sleeve, said bracket being free to slide up and down upon said sleeve, manually-con-
45 trolled means including a lever for adjusting the bracket up and down upon the sleeve and thereby raising and lowering the plow, and a tongue connected with the upper end of said stem.
6. A wheeled plow comprising a suitable plow and beam, a plurality of supporting-wheels including a rear furrow-wheel, a vertically-disposed stem upon which said furrow-
50 wheel is mounted, a sleeve on said stem, a bracket connecting the sleeve with the plow and beam, manually-controlled means for adjusting the bracket upon the sleeve and thereby raising and lowering the plow, and a driver's seat secured to said sleeve, the said furrow-wheel thereby supporting the weight of the driver, and being free to turn without altering the position of the driver.
7. A wheeled plow comprising a suitable plow and beam, front and rear furrow-wheels, a land-side wheel, a couple of vertically-disposed stems upon which said furrow-wheels are mounted, a crank-axle upon which the land-side wheel is mounted, a sleeve on the stem of the rear furrow-wheel, a bracket rigid with the plow and beam but free to slide up and down upon the stem of the front furrow-wheel, a bracket rigid with the plow-beam but adapted to slide up and down upon said sleeve, a driver's seat secured to said sleeve, a lever connected and arranged for simultaneously rotating said crank-axle and adjusting said brackets vertically upon said stems, and an auxiliary lever for independently controlling the land-side wheel.
8. A wheeled plow comprising a suitable plow and beam, front and rear furrow-wheels, vertically-disposed stems for said wheels, a tongue connected to impart a rotary motion to said stems, brackets rigid with the beam but free to slide up and down upon said stems, a land-side wheel having a shifting connection with the beam, a lever for simultaneously controlling all three wheels, and an auxiliary lever connected and arranged for adjusting the land-side wheel without causing said brackets to slide up and down on said stems.
9. A wheeled plow comprising a suitable plow and beam, front and rear furrow-wheels, a land-side wheel, a foot-lever for simultaneously controlling all three wheels, an auxiliary lever for independently controlling the land-side wheel, and another auxiliary lever adapted to assist the foot-lever in raising and lowering the plow and beam.
10. A wheeled plow comprising a suitable plow and beam, front and rear furrow-wheels, a land-side wheel, a foot-lever connected and arranged for simultaneously controlling all three wheels, an auxiliary lever for independently controlling the land-side wheel, and another auxiliary lever for assisting the foot-lever in raising and lowering the plow, said last-mentioned auxiliary lever being arranged to be connected with, or disconnected from, the connection between the foot-lever and the wheels, whereby said second auxiliary lever may be rendered operative or inoperative to control the wheels.
11. A wheeled plow comprising a suitable plow and beam, front and rear furrow-wheels, a land-side wheel, a pair of sprocket-wheels connected and arranged for causing a relative shifting between the wheels and plow and

beam, a belt connecting said wheels, an arm connected with said belt and also with said land-side wheel, and a lever connected with said arm and thereby operative to simultaneously adjust all of said wheels.

12. A wheeled plow comprising a suitable plow and beam, front and rear furrow-wheels having direct shifting connections with plow-beam, a land-side wheel having a direct shifting connection with the plow-beam, manually-controlled means for simultaneously controlling all shifting connections so as to raise and lower the plow, and adjustable connections whereby the rear furrow-wheel may be adjusted laterally with relation to the plow.

13. In a wheeled plow the combination of a plow and plow-beam, front and rear furrow-wheels, a land-side wheel, a crank-axle upon which said land-side wheel is mounted, vertically-disposed stems upon which said furrow-wheels are mounted, brackets rigid with the plow-beam but free to slide up and down on said stems, crank-arms and pitman arranged to cause the brackets to slide up and down on the stems when the crank-arms are rotated, an arm rigid with said crank-axle, a foot-lever pivoted to the plow-beam, a link connecting said foot-lever with said arm, the joint between the foot-lever and link being adapted when centered to lock the plow in the ground, wheels connected with said crank-arms, a belt connecting said wheels, and means for connecting said belt, arm on said axle, whereby

the said foot-lever is operative to simultaneously control all three wheels. 35

14. A wheeled plow comprising a suitable plow and plow-beam, a front furrow-wheel and a rear furrow-wheel and a land-side wheel, a vertically-disposed stem on which said rear furrow-wheel is mounted, a bracket rigid with the plow-beam, the said stem being mounted to turn or rotate in said bracket, and manually-controlled means including a lever for simultaneously controlling all three wheels, and for causing said bracket to slide up and down on said stem. 40 45

15. A wheeled plow comprising a suitable plow and beam, a plurality of supporting-wheels including a rear furrow-wheel, a vertically-disposed stem on which said wheel is mounted, a sleeve in which said stem is mounted to turn or rotate, a bracket rigid with the plow-beam and adapted to slide up and down upon said sleeve, manually-controlled means including a lever for adjusting the bracket up and down upon the sleeve and thereby raising and lowering the plow, said means including a member connected with and adapted to hold the sleeve against rotation, and a tongue connected with the upper end of said stem. 50 55 60

Signed by me at Chicago, Illinois, this 5th day of August, 1902.
